UNITED STATES PATENT OFFICE.

ROSCOE C. PFLEAGER, OF CLEVELAND, OHIO, ASSIGNOR TO BENJAMIN F. KLEIN, OF CLEVELAND, OHIO.

DESIGN FOR A LIGHTING FIXTURE.

Application filed July 10, 1922. Serial No. 3,017. Term of patent 7 years.

To all whom it may concern:

Be it known that I, ROSCOE C. PFLEAGER, a citizen of the United States, residing in Cleveland, in the county of Cuyahoga and State of Ohio, have invented a new, original, and ornamental Design for Lighting Fixtures (C. 6,154), of which the following is a specification, reference being had to the accompanying drawing, forming part thereof.

The figure represents an elevation of the new fixture.

I claim:

The ornamental design for a lighting fixture, substantially as shown.

Signed by me, this 2nd day of June, 1922.
ROSCOE C. PFLEAGER.
